UNITED STATES PATENT OFFICE.

GEORGE P. KINGSBURY, OF BROOKLYN, NEW YORK, ASSIGNOR TO MERGENTHALER LINOTYPE COMPANY, A CORPORATION OF NEW YORK.

LINE-CASTING MACHINE.

1,076,433.

Specification of Letters Patent.

Patented Oct. 21, 1913.

Application filed December 30, 1911. Serial No. 668,651.

To all whom it may concern:

Be it known that I, GEORGE P. KINGSBURY, a citizen of the United States, and a resident of the borough of Brooklyn, county 5 of Kings, and State of New York, have invented a new and useful Improvement in Line-Casting Machines, of which the following is a specification.

This invention has reference to line casting machines of the Mergenthaler type, such 10 as shown in Letters Patent of the United States No. 436,532, and kindred machines, in which circulating matrices for the type characters are released from a magazine by 15 escapements controlled by corresponding finger keys, that they may be assembled temporarily in line. As certain of the characters, such as "e," "i," etc., are used more frequently than others, it is the practice to 20 provide in the magazine two channels for each of these characters, and to provide shifting connections from a single finger key to deliver the matrices from the two channels alternately, as shown, for example, in 25 Letters Patent of the United States to Mergenthaler No. 658,740, and British Patent No. 19,017 of 1905. In these mechanisms the shifting of the finger key connections is effected at long intervals, usually at the 30 completion of each line of composition. Owing to this long interval there is in certain classes of composition the liability of one channel being exhausted before the shift occurs, in which event the operation of 35 the finger key will fail to deliver a matrix.

The object of my invention is to provide a simple mechanism by which the shifting of the finger key connections from one escapement to another may be effected at positive and shorter intervals.

In all these machines there is a mechanism controlled by a finger key, commonly known as the "space key", for delivering from their magazine expandible spacers or 45 justifiers into the composed line, between the word groups of matrices. Ordinarily this mechanism is operated several times during the composition of each line, generally after every fourth or fifth character.

50 My invention consists broadly in the combination of this space-delivering mechanism with the matrix delivering devices in such manner as to shift the finger key connections. This results in the delivery of matrices from one channel during the composition of one word, and from the other chan-

nel during the composition of the next word, and so on alternately, this frequent changing preventing the possibility of the matrices being exhausted in either channel. 60

It will be manifest to the skilled mechanic after consideration of this specification and the accompanying drawings, that my invention is susceptible of embodiment in numerous equivalent forms. 65

In the drawings I have shown the invention in its preferred form, as combined with the mechanism of a commercial Mergenthaler machine of the present day.

In the drawings, Figure 1 is a perspective 70 view showing a portion of the matrix delivering mechanism, space delivering mechanism, and finger key connections of a Mergenthaler machine with my improvement applied thereto. Figs. 2, 3 and 4 are side 75 elevations illustrating the device for shifting the connections in their various successive positions. Fig. 5 is a vertical cross section on the line 5—5, Fig. 3.

Referring to the drawings; A, A represent 80 portions of the frame work of the machine; B the inclined channeled magazine in which the matrices C, are stored, and from which they are delivered one at a time by the vibratory escapements E, one 85 for each channel.

F are springs which hold the escapements normally in the positions shown.

G, G', G'', etc., are vertically guided reeds which lift the rear ends of the escapements 90 momentarily to release the matrices.

H is a magazine containing the expandible wedge spacers I, which are delivered therefrom one at a time by the pawl J, that they may descend by gravity to the matrix 95 line in course of composition. These spacers, and the mechanism for delivering them, may be identical with those shown in Letters Patent of the United States No. 436,532, now in common use, or of any 100 other suitable construction. The pawl J is actuated by a lever L, pivoted to the main frame, and, in turn, actuated by a vertical reed M, jointed thereto and extended downward, to be operated by the 105 keyboard connections. The keyboard mechanism for operating this reed, and also for operating the escapement actuating reeds G, G', etc., is power-driven, and controlled by finger keys. In the form shown, they 110 are substantially identical with those shown in United States Letters Patent to Dodge

No. 530,931, with the exceptions hereinafter noted.

Each of the escapement reeds G, G', etc., is actuated by a vertically guided bar N, lying thereunder, and actuated in its turn by a lifting yoke O, pivoted at one end, and containing a cam P, which overlies a constantly driven rubber-covered roll Q, this roll extending the entire width of the 10 keyboard, to operate the series of yokes.

Each yoke is held normally in an elevated position, to keep the cam out of contact with the roll, by an angular dog R, pivoted on the main frame and controlled 15 by the vertical slide S, connected to a finger key. When the key is actuated it lifts the bar S, which causes the dog R to release the yoke O, which falls and permits the cam P to contact with the roll Q, where- 20 upon the frictional engagement causes the cam to receive a rotary motion from the roll on which it is supported. Owing to the eccentricity of the cam, its rotation causes the yoke O to rise at one end above 25 its original position, lifting the bar N, which in turn lifts the reed G, causing an escapement to be actuated, and a matrix to be released. When the yoke descends it is arrested in its original position by the 30 dog R.

In the ordinary machines the reeds G are continued downward, and each one connected with a cam yoke. In my mechanism the reeds are terminated, as shown, 35 above the yoke, and the bar N interposed. The lower end of the bar N is mounted in a fixed guide, but the upper end is extended through a horizontally movable guide U, so that the upper end of the bar may 40 be shifted sidewise, that it may operate either one of two reeds, these reeds in turn actuating the escapements of two channels, which will contain matrices for the same character. It is the shifting of this guide 45 by the spacer mechanism, when it is actuated, that constitutes the leading part of my invention. The connections may be of any character which will cause the shifting of the bar N when the mechanism is op- 50 erated to release a spacer from the magazine H. In the form shown the mechanism consists simply of a lever V, pivoted at v, to the main frame, and jointed at its lower end to the guide U, or otherwise connected 55 therewith. At the upper end the lever V is forked, and provided on the inner end of its arms with lips v'. To the reed M, which it will be remembered effects the release of the spacers, I pivot two pawls 60 m and m', weighted at the lower end, projecting in opposite directions, and acted upon by springs m², which normally prevent them from rising above the positions indicated. As the reed M rises the two 65 pawls act alternately on the upper ends of

the lever V, causing it to vibrate and shift the guide U and bar N to and fro.

In detail, the operation is as follows: Assume the reed M to be in the lower position, as shown in Figs. 1 and 2, and the bar N to be in its left hand position. When the reed is raised, carrying with it the pawl m, the end of the latter acts beneath the lip on the left side of the lever V; and as the reed and pawl continue their upward movement the pawl, being compelled to turn on its pivot, approaches the horizontal position, as shown in Fig. 3, and pushes the end of the lever V to the left, causing its lower end to shift the guide U and bar N to the right, so that matrices will be released from the right hand channel of the magazine. During this action the right hand pawl m' rises inactively above the lever V as shown. When the reed M de- 75 scends the pawls are again carried downward, and the right hand pawl m' engages beneath the lip v', which has been shifted over by the movement of the lever. When the reed M is next raised, to drop the next spacer into the line of matrices, the pawl m' acting beneath the lip v', and gradually assuming a horizontal position, pushes the upper end of the lever V to the right, causing its lower end to move 80 to the left, thereby shifting the guide U and the bar N to their original positions, so that when a finger key is actuated matrices will be delivered from the left hand channel of the magazine. Thus it 85 will be seen that the action of the space key serves to change the delivery of matrices from one channel in the magazine to the other each time the space key is actuated, which is ordinarily after the composition of 90 each word in the line. 95

It will be observed that the shifting movement is effected by power-driven devices, and that the finger key simply controls the actuation of these devices, there being no additional labor imposed upon the key, or the operator. For rapid composition it is im- 100 portant that all the keys in the keyboard, to operate easily, should offer practically the same resistance. If one key offers more resistance than another it is found to interfere materially with the speed of composition, causing hesitation on the part of the operator. 115

It will be manifest to the skilled mechanic 120 that the lever and pawls herein shown may be replaced by other equivalent devices for imparting motion from the spacer-releasing mechanism to the devices for shifting the escapement connections without passing be- 125 yond the scope of my invention.

Having described my invention, what I claim is:

1. In a machine of the class described, the combination of two distinct matrix releasing 130

devices, a single finger key to control them, and a space delivering mechanism adapted to be operated after the composition of each word and arranged to shift the connection 5 between the finger key and matrix releasing devices, substantially as described; whereby the key is enabled to actuate the two matrix releasing devices alternately.

2. In a machine of the class described, the 10 combination of two magazine channels and escapements, two actuating reeds for the escapements, a finger key, connections through which the key controls said escapements one at a time, and a space delivering mechanism 15 adapted to be operated after the composition of each word and arranged to shift said key connections; whereby the key is caused to deliver matrices from one channel during the composition of one word and from the 20 other channel during the composition of the next word, and so on alternately.

3. Two escapements and actuating means therefor comprising a single shiftable connection for operating them alternately, in 25 combination with space delivering devices adapted to be operated after the composition of each word and arranged to shift said connection each time that a space is delivered.

30 4. Two escapements to deliver matrices from separate channels, actuating devices therefor, and a single means for controlling them, in combination with a space delivering mechanism adapted to be operated after the 35 composition of each word and which shifts the said controlling means and thus effects the action of said escapements alternately.

5. In a machine of the class described, the 40 combination of manually operable means for delivering matrices from different magazine channels, means for delivering spacers between the composed words, and connections

whereby the spacer delivering means will cause the matrix delivering means when operated to deliver matrices from one channel 45 during the composition of one word and from another channel during the composition of a succeeding word.

6. In a machine of the class described, the combination of two matrix escapements, an 50 actuating device therefor, and means for connecting said device with the escapements alternately during the composition of a line, the said means being operated after the composition of each word in the line. 55

7. In a machine of the class described, finger key mechanism for delivering matrices from two magazine channels, and a finger key mechanism for delivering spacers adapted to be operated after the composition 60 of each word, the latter mechanism arranged to control operative relation of the former to the respective channels, substantially as described.

8. In a machine of the class described, two 65 escapements for delivering matrices, power driven actuating devices therefor, and a finger key to set them in motion, in combination with power driven mechanism to release spacers from their magazine adapted to be 70 operated after the composition of each word, the last named mechanism arranged to shift members of the power driven devices in order to cause the operation of the two escapements one at a time. 75

In testimony whereof I hereunto set my hand this twenty third day of December, 1911, in the presence of two attesting witnesses.

GEORGE P. KINGSBURY.
